CLAIM

(57) The ornamental design for a rotating buckle, as shown and described.

DESCRIPTION

FIG. 1 is a bottom, front and left side perspective view of a rotating buckle showing our new design;

FIG. 2 is a top, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded view thereof.

The broken lines in the drawings illustrate portions of the rotating buckle and form no part of the claimed design.
